UNITED STATES PATENT OFFICE.

HARRY C. HASKINS, OF MILWAUKEE, WISCONSIN.

TELEPHONE SYSTEM.

SPECIFICATION forming part of Letters Patent No. 242,311, dated May 31, 1881.

Application filed October 2, 1880. (No model.)

To all whom it may concern:

Be it known that I, HARRY C. HASKINS, of Milwaukee, in the county of Milwaukee, and in the State of Wisconsin, have invented certain new and useful Improvements in Telephone Systems; and I do hereby declare that the following is a full, clear, and exact description thereof.

My invention relates to the working of telephone-exchanges; and it consists in a system by which the operators in the central office may silently communicate with each other in their work of connecting and disconnecting subscribers with each other.

In the drawings, Figure 1 is a plan view of a Gilliland switch-board, and Fig. 2 a plan view of an operator's table.

It has heretofore been one of the great obstacles to the successful working of telephone-exchanges that the announcement, orally and by writing, of the connections and disconnections has been accompanied by a great deal of confusion; and the object of my invention is to overcome this, which I do as follows, illustrating by a Gilliland switch-board: This switch-board I place in the operator's room of the central office, connecting it with the table by wires I K. Upon the table I place an annunciator, A, into which wire K enters, the wire c connecting the annunciator A with switch B, which turns on a vertical axis or pivot to connect the annunciator A with either of buttons a b. A wire, H, extends from button b to target G' on annunciator E, and when this target is set or in its raised position it is connected with the electrical power F through spring S and wire G, the power F being suitably grounded. Line I simply passes from the switch-board to button a and plate C'.

The generator Y is connected, when desired, with annunciator E by line O, key D, and line L, and annunciator E is grounded by wire or line E'.

Just above the annunciator E, which in practice I propose to arrange just over the switch-board, I attach by a suitable bracket, R, a spring, S, and this spring, when the target is set or in its raised position, will complete a circuit with the annunciator A from the electrical generator F when the switch B is on button b, and through it to the switch-board.

The operation of my device is as follows: No. 4 desiring to communicate makes the usual call on central office, and, being answered, says "Connect me with No. 5." The operator at 55 the switch-board will then insert connecting-plug P at the intersection of line 4 with strip C, and plug P' at intersection of line 5 with strip C', thus completing a circuit which, starting from earth, passes through generator F, 60 line G, to spring S, target G', line H, to b, across switch B, through annunciator A, and through line K, to end of strip C'. Now the generator F is in circuit and gives the alarm at station on line 5, the passing current having caused A's target to drop, notifying the operator at table of the connection. The operator then moves the switch B to button a, which places lines 4 and 5 in direct communication with each other and cuts off the calling-power. The operator at the table will now 70 wait for the parties to indicate that they are through talking by giving a disconnecting-signal, or he may connect his local telephone with plate C'' and listen for the cessation of the 75 conversation, and when this occurs he presses upon key D, completing the circuit from generator Y through line L to E, causing the target G' to fall and break connection with power F, the fall of the target also notifying the boy at 80 the switch-board that the plugs may be taken out and 4 and 5 disconnected. This he does, and then sets the target G', seeing which the operator at table turns the switch B back to b, thus again putting the calling-power in readiness for another connection.

I use an annunciator, E, for each pair of horizontal conducting-strips a' a' B' B' C C'.

W represents a local telephone of the ordinary construction, grounded as usual. X is a 90 wrapped wire depending therefrom and terminating in a metallic plug, which, when the operator places it upon the plate C'', will bring the local telephone in circuit with the lines I and K and enable the operator to ascertain 95 when the conversation is at an end, so that the operator may by pressing upon D complete the circuit from Y to E through line L, causing the target G' to drop.

I am aware that I am not the first to have 100 connected the switch-board plates in pairs with an operator's table provided with an apparatus

for calling and connecting subscribers, and I therefore disclaim the same.

What I claim as my invention, and desire to secure by Letters Patent, is—

- 5 1. The combination, in a telephone system, of a switch-board and connecting-plugs, annunciator A, and its target, switch B, buttons *a* *b*, annunciator E, generator F, and connecting-lines, whereby the operator at table is enabled to complete connection between two subscribers and at the same time cut off the calling-power, substantially as described.
- 10 2. The combination of switch B, buttons *a*

b, plate C'', and lines connecting them with the switch-board.

- 15 3. The combination of generator Y, key D, annunciator E, having target G', spring S, and battery-power, with the button *b*, connecting-lines, and annunciator A, as set forth.

In testimony that I claim the foregoing I have hereunto set my hand this 24th day of September, 1880.

HARRY C. HASKINS.
